ERNEST COLEGATE, OF GILLINGHAM, ENGLAND.

FASTENING OR SEALING BOXES, PACKETS, WRAPPERS, AND THE LIKE.

1,076,955.

Specification of Letters Patent. Patented Oct. 28, 1913.

Application filed July 5, 1912. Serial No. 707,879.

To all whom it may concern:

Be it known that I, ERNEST COLEGATE, a subject of the King of England, and residing at Gillingham, Kent, in England, have invented certain new and useful Improvements in the Fastening or Sealing of Boxes, Packets, Wrappers, and the like, of which the following is a specification.

This invention relates to the fastening or sealing of boxes, packets, wrappers and the like, and has for its object to enable snap fasteners to be satisfactorily employed for this purpose.

Hitherto closing tags or flaps, each carrying one member of the snap fastener have been connected to a wall of the box and portion of the lid or cover respectively in such a way that the two members of the snap fastener could be made to engage when the box was closed. Such an arrangement has proved unsatisfactory, since the tags, which were formed of paste-board, linen, stout paper or the like had first to have the snap members riveted or otherwise connected to them before they could be applied to the box, and further it was necessary to attach the tags to the box before the latter was completed. Consequently difficulty was experienced in making the two members of the snap fastener to register, with the result that the closing device was rendered useless.

According to this invention one member of a snap fastener is attached to the lid or closing flap of a box, packet or wrapper, the other member of the fastener being attached to the wall or other part of the box, this wall being then cut in the neighborhood of the fastening member it carries so as to form a tag or the like, which is integral with the wall, and brings the two portions of the fastening into the necessary position for engagement, whereby the box is effectively secured when closed. By forming a tag in one with a portion of the wall of the box in this manner and bending the tag so as to engage the outer surface of the lid or closing flap, the portion of the latter which carries the corresponding member lies between the main portion of the wall which it covers and the under-surface of the tag formed from a portion of this wall. By so forming the tag it is possible to secure the lid of a box in place merely by applying pressure to the two portions of the snap fastener, and that portion of the fastening

member which is carried by the lid or cover is adequately supported by the other portions of the wall at the moment when pressure is applied, even when the box or packet is empty or contains an article which offers no resistance to pressure.

In the accompanying drawings, Figure 1 is a perspective view of one form of box according to this invention, the box being shown open. Fig. 2 is a similar view of the same box closed. Fig. 3 is a perspective view of another type of box closed. Figs. 4 and 5 show in section on an enlarged scale the two portions of the snap fastener in their inoperative and operative positions respectively. Fig. 6 is an elevation of the end wall of a folding box before being folded. Fig. 7 is a cross section after this wall has been folded into its operative position, and Fig. 8 is a perspective view of a wrapper or like packet provided with a closing tag according to this invention.

In the construction illustrated in Figs. 1 and 2 the box is formed of leather-board or stout paste-board and has the stud portion A of a snap fastener attached to its front wall B at a definite distance from the upper edge thereof, this wall being cut in a direction parallel with the height of the box on either side of the stud so as to form a tag B' which is integral with the front wall of the box. The flange C' on the front of the lid C, which in the example illustrated is of the hinged variety, has a socket portion D of a snap fastener attached to it, preferably by some convenient eyeletting machine, the distance between the center of the socket portion D and the top of the lid coinciding with the distance between the center of the stud member A and the upper edge of the front wall B of the box. It will thus be seen that when the lid C is closed, if the tag B' formed in the manner described is bent outward as shown in Fig. 1 and then made to lie against the outer face of the flange C', the two portions A, D of the snap fastener can be made to engage on being pressed together (Fig. 5) so that the box is securely closed. Since the socket portion D of the fastener is attached only a short distance below the top of the box, and as the flange C' in which it is formed is supported by the upper edge of the front wall B' of the box, it is adequately supported at the moment when pressure is applied and does not tend

to yield and so prevent the two portions of the snap fastener being engaged even when the contents of the box do not afford any support.

6 The front wall B is conveniently cut in the same machine which applies the stud member A, the two operations being simultaneous or in rapid succession. If desired the upper ends of the tag may be rounded as shown in Fig. 3 and the tag formed nearer the base of the front wall should the flange on the box lid be of considerable depth. Fig. 3 shows such a tag for use in connection with a box where the lid is entirely removable and of approximately the same depth as the box itself.

If desired the base of the tag may be grooved as at B² in Figs. 4 and 5 to facilitate the ease with which it may be bent outward and also give an indication as to where the tag is to be cut through when the box is to be opened.

25 The tag may be ornamented in any convenient manner and if desired may be impressed when having the stud applied thereto, with directions as to how the box is to be opened or to imitate say a leather strap. The arrangement is such that the tags are not bent outward into their operative position until it is required to seal the box, so that when the boxes are stored awaiting use the two parts of the snap fastener are in the position shown in Fig. 4 when no accidental engagement between the two 30 members can take place by reason of the engaging surfaces being entirely out of contact with one another.

In some types of folding boxes the end walls are formed of double thickness, the 40 inner wall being bent over along the upper edge of the box to assume a position parallel to the outer wall and thus serve to retain the side walls of the box in an extended state. Such an end wall is shown in its extended state in Fig. 6, where the cardboard E constituting the end wall is provided with two longitudinal grooves E' E². A tag B' is cut in the lower portion of the wall E and provided with a snap fastener A as in the 45 construction already described and the portion of the wall F between the grooves E' E² is then folded into the position shown in Fig. 7 that is to say into a plane parallel with the front wall E so that the groove E² forms the upper edge of the box. The portion G is then bent along the groove E' at right angles to the plane of the wall F so that the three parts of the wall E, F, G, assume the position shown in section in Fig. 7. 50 When the end wall is so folded it will be seen that an inner protective wall is provided which prevents damp or dust entering the box through the opening formed by the tag. The groove E' and extension or 55 foot G may be omitted if desired but its

provision acts as an additional security and further by engaging the bottom of the box increases the area of the surfaces in contact.

Though described above with reference to boxes having flanged lids the invention is 70 equally applicable to all packets or wrappers where a closing flap or cover is folded down upon another flap or wall to inclose anything therein. For instance if a plain cardboard wrapper such as those employed for 75 transmitting photographs through the post is to be closed in accordance with this invention the socket portion of the fastener is conveniently applied to the closing flap at a given distance from its free end the stud member being attached to the under flap or rear wall of the wrapper at a corresponding distance from the free edge of the tag which is formed in one with such rear wall. Such an arrangement is shown by way of 80 example in Fig. 8 which illustrates a wrapper for inclosing a book. This arrangement comprises a single piece of cardboard H provided with a closing flap H' and an under flap or rear wall H². The socket portion D of a snap fastener is attached to the closing flap H' in the usual way and a rounded tag to which the member A of the fastener is secured is formed in the rear or under wall H². The wrapper is provided 85 with end flaps H⁸ and is preferably corrugated or grooved at H⁴ in the known manner to accommodate the book or other article which it is intended to inclose. Where the tag is of the straight form shown in Figs. 1 90 and 2 the length of the cuts constituting the tag determines the extent to which the closing flap or cover H' overlaps the under wall H².

95 It will be understood that any number of closing tags may be formed in the wall of the box in the manner described and that though primarily intended for use in connection with snap fasteners which cannot be opened when once closed, the invention is 100 also applicable to snap fasteners of the type which can be opened as often as desired. Further, where boxes, for instance those containing samples, are to be sent through the post and are to be returned, an additional tag and corresponding snap fastener in the lid may be provided but not used in the first instance, this fastening being employed when the packet is returned.

105 Though the stud member has been described as being applied to the tag it will be understood that the socket member may be formed on the tag and the stud on the lid if found desirable. Further the forms of packet which can be fastened in this manner 110 may vary considerably and the position of the fastening members on the packets to be closed may be varied in many respects to 115 suit requirements without departing from this invention.

In some cases a label or addressing tag may be attached to the box simultaneously with the closing operation thereof, the label being eyeleted and the head of the stud 5 being made to engage the eyelet and so grip the latter between the under surface of the closing tag and the outer face of the box, alternatively the addressing label may be attached to the box lid or its closing tag by 10 being riveted thereto simultaneously with the respective portion of the snap fastener.

What I claim as my invention and desire to secure by Letters Patent is:—

1. In a box, the combination with a 15 flanged lid carrying the socket portion of a snap fastener in its flange, of a closing tag, cut out from the wall of the box, carrying the stud portion of the snap fastener and adapted to be brought against the outer surface of the flanged lid to engage the fastening member carried thereby as set forth.
- 20

2. The herein described box comprising a body and a cover, the body having a tag cut from a side wall and adapted to extend within the cover or to be deflected outwardly 25 to permit a portion of the cover to extend beneath said tag and over the outer face of the wall from which the tag is formed at both sides of the tag, and a snap fastener having one member attached to and projecting from the inner surface of the tag and the other secured to the section of the cover that is adapted to be positioned beneath the tag.

In testimony whereof I have signed my 35 name to this specification in the presence of two subscribing witnesses.

ERNEST COLEGATE.
